UNITED STATES PATENT OFFICE.

CHARLES J. THORP, OF DETROIT, MICHIGAN.

COMPOSITE METALLIC PLATE.

1,168,441.

Specification of Letters Patent. Patented Jan. 18, 1916.

Original application filed November 23, 1914, Serial No. 873,428. Divided and this application filed January 11, 1915. Serial No. 1,692.

To all whom it may concern:

Be it known that I, CHARLES J. THORP, a citizen of the United States of America, residing at Detroit, in the county of Wayne 5 and State of Michigan, have invented certain new and useful Improvements in Composite Metallic Plate, of which the following is a specification, reference being had therein to the accompanying drawings.

10 This is a division of my application filed Nov. 23, 1914, Serial No. 873,428.

This invention relates to a composite metallic plate, and the object of my invention is to provide a plate of gold and silver which 15 can be used for various purposes, but which has been especially designed for the art of dentistry.

As illustrating an instance of the use of a plate in accordance with my invention, reference will be had to the drawing, wherein—

20 Figure 1 is a plan of a composite plate produced by a metallurgical operation; Fig. 2 is a side elevation of the same; Fig. 3 is a plan of a disk or blank cut or stamped from the plate, and Fig. 4 is a vertical sectional view of a tooth crown or shell produced by stamping and cupping the disk shown in Fig. 3.

25 Selecting a bar of gold about one quarter inch thick and 22 carat fine, and a bar of granular pure or fine silver, said silver is placed upon the gold. The bar of silver is about the same thickness as the gold. The bar of silver is then subjected to the action of heat, for instance by a torch, to the extent that the bar of silver is melted and soldered on the gold bar. That is, the confronting sides of the bar form a homogeneous connecting tissue without affecting the outer 30 sides of the ingot thus produced, the outer sides being maintained gold and silver respectively. When the silver has sufficiently cooled, the ingot is subjected to a rolling action with sufficient pressure brought to bear to reduce the combined bars to about thirty gage with an equal gage of each metal maintained or approximately so, and

in this manner a sheet is produced having gold and silver sides designated 1 and 2 respectively. From the composite sheet or 50 plate thus produced one or more disks or blanks 3 can be cut and stamped and then the disk or blank subjected to the action of the dies or forming members whereby the disk is stamped to form a crown or shell 4 55 having a silver lining.

Considering the crown or shell from a dental standpoint, the metal composition possesses indispensable characteristics and the following may be cited:—first, it reduces 60 the amount of gold heretofore necessary in the formation of a tooth crown or shell without sacrificing strength and other prerequisites; second, it provides a tooth crown or shell that has a lining which resists amalgamation which would occur if amalgam was used in connection with a crown composed 65 simply of gold; third, such a composite tooth crown will resist the force and wear of mastication and thereby preclude any danger of 70 the crown being completely worn through, and fourth, a simple and inexpensive crown is produced that can be easily shaped to conform to the grinding or irregular surface of a tooth.

75 I am aware that platinum has been used in connection with gold tooth crowns or shells, but such compositions have many disadvantages. In the first place, the cost of platinum prohibits extensive use. For instance, sixty 80 dollars an ounce as compared with silver at fifty cents an ounce. Second, the many inequalities between gold and platinum will not permit of its being properly shaped or swaged since the melting point of platinum 85 is much higher than that of gold, and it is simply impossible to fuse these two metals and maintain an equal gage for each.

I attach considerable importance to the fact that in uniting the gold and silver into 90 a single sheet, only the confronting sides are homogeneous or composite, and the outer sides maintain their distinctive qualifications. The uniting of the confronting sides

of sheets of gold and silver permits of the composite sheet being bent or shaped without any danger of the two metals separating, as would occur if the sheets or plates were 5 joined by a rolling or other process.

What I claim is:—

A bimetallic plate, composed of gold and silver fused together to form a plate having

opposite exposed faces with one exposed face silver and the other exposed face gold.

In testimony whereof I affix my signature in presence of two witnesses.

CHARLES J. THORP.
